UNITED STATES PATENT OFFICE

MYRON SANDLER, OF NEW YORK, N. Y., ASSIGNOR TO CHARLES S. ALBERT, OF SPRINGFIELD, MASSACHUSETTS

BUCKLE DEVICE

Application filed June 16, 1931. Serial No. 544,727.

This invention relates to improvements in fastening devices and is directed more particularly to buckles for belts, straps and the like such as are used in connection with clothing and apparel.

The principal objects of the invention are directed to the provision of a buckle structure wherein a pair of buckle elements are constructed and arranged for fastening together in such a way that the said elements are held against relative movements and present the appearance of a unitary one-piece buckle.

The features of the invention are accomplished by the provision of separable buckle elements which have overlapping and interlocking portions and fastening means therefore whereby the parts may be held together against relative shifting movements in such a manner as to present the one piece unitary effect.

The novel features of the invention will be more fully hereinafter referred to in connection with the accompanying description of the preferred form of the invention which for purposes of disclosure is shown in the accompanying drawings wherein:

Fig. 1 is a plan view of a buckle device embodying the novel features of the invention.

Fig. 2 is a plan view of one of the buckle elements.

Fig. 3 is an edgewise view of the other of the buckle elements, and

Fig. 4 is an edgewise view of the buckle elements in secured together relation.

Referring now to the drawings more in detail the invention will be fully described.

The buckle device of the invention comprises separable buckle elements 2 and 4 which are constructed and arranged for overlapping and interlocking engagement so that when connected together they present the appearance of a single unitary buckle as shown in Fig. 1.

The element 4 on its upper or outer side and at its inner end is provided with a depression or recess 6 in which is located a prong receiving socket indicated at 8. This recess 6 extends inwardly from the inner end or side of the buckle element 4 and is for re-

ceiving the forward or inner tongue end 12 of the other buckle element 2. The recess 6 may be of any shape desired while the forward or inner tongues 12 of the element will preferably be of such a shape as to fit snugly 55 within the said recess.

It is desirable that the upper surfaces of the elements 2 and 4 be substantially flat or flush so as to carry out the one-piece effect when the elements are secured together. As 60 shown the sides of the recess and tongue are preferably disposed in an angular relation to prevent shifting of the buckle parts when in overlapping relation.

A prong or tip 14 extends downwardly 65 from the inner tongue portion 12 of the buckle element 2 which is releasably receivable in the socket 8. When the portion 12 of the element 2 is disposed within the recess 6 the prong 14 may be inserted in the socket 8 70 and co-operates therewith to hold the elements in their overlapping and interlocking relation as best shown in Fig. 1. When so overlapped the parts are held against turning movements by reason of the angularly 75 disposed sides of the recess and tongue.

Straps or bars represented at 16 may be carried by the rear faces of the elements 2 and 4 by the means of which the elements may be secured to the ends of a belt, strap or other object which ends are to be joined together by means of the buckle.

Other means than the members 16 may be employed for fastening the buckle elements 2 and 4 to a strap or belt, but will form no 85 part of the present invention.

The buckle elements 2 and 4 may be made of various materials and they may be made in various shapes and sizes depending of course upon the use for which the buckle structure is 90 to be employed.

The upper or outer faces of the elements may be suitably engraved or may carry various kinds of ornamentation all as may be desired for decorative purposes.

As has been stated the recess may take various forms and the tongue part of the element overlapping interfitting therewith may be correspondingly shaped so that the elements when placed in overlapping and interlocking 100

relation will be held against relative shifting movements, and present the unitary single piece appearance intended.

In the form of the invention shown the recess 6 is formed with angularly disposed sides as is the tongue portion 12 so as to prevent shifting movements of the elements 2 and 4.

Having described the invention in the form at present preferred, what I now desire to claim and secure by Letters Patent of the United States is:

1. A buckle device comprising in combination, a pair of separate buckle elements, one of said elements provided with a recess in the upper side thereof extending inwardly from an inner side edge for receiving in overlapping relation a tongue portion of the other element, the sides of said recess and tongue having complementary portions whereby the elements are held against relative movement and co-operating fastening devices associated with said tongue and recess to hold said elements in releasable engagement with the tongue in said recess.
2. A buckle device consisting of two separable elements, one of which is provided with an obtusely angled recess extending outwardly from the inner part of the element to one side into which fits the other element, one end of which is complementary to the recess angle and releasable fastening means associated with said elements to prevent separation thereof.
3. A buckle device comprising in combination, a pair of separate buckle elements, one of said elements provided with a recess extending inwardly from an inner side edge for receiving in overlapping relation a tongue portion of the other element, the sides of said recess and said tongue having angularly disposed complementary portions whereby the elements are held against relative movement and the said tongue and recess having a co-operating socket and prong associated therewith to hold said elements together.

In testimony whereof I affix my signature.
MYRON SANDLER.
